LAMP TABLE

William I. Smith, Perrysburg, Ohio, assignor to The Hetrick Manufacturing Company, Toledo, Ohio, a corporation of Ohio

Application October 11, 1954, Serial No. 32,617

Term of patent 14 years

(Cl. D33—14)

FIG. 1

FIG. 2.

FIG. 3.

To all whom it may concern:

Be it known that I, William I. Smith, a citizen of the United States and a resident of Perrysburg, Wood County, Ohio, have invented a new, original, and ornamental Design for a Lamp Table, of which the following is a specification, reference being had to the accompanying drawing, forming a part thereof.

In the drawing:

I claim:

The ornamental design for a lamp table, as shown.
